UNITED STATES PATENT OFFICE.

JACOB P. DECKER, OF NEW YORK, N. Y., ASSIGNOR TO E. & H. T. ANTHONY & COMPANY, OF SAME PLACE.

PHOTOGRAPHIC-PLATE-HOLDING APPARATUS.

SPECIFICATION forming part of Letters Patent No. 402,512, dated April 30, 1889.

Application filed December 3, 1888. Serial No. 292,453. (No model.)

To all whom it may concern:

Be it known that I, JACOB P. DECKER, a citizen of the United States, and a resident of New York city, in the county of New York 5 and State of New York, have invented certain new and useful Improvements in Photographic Apparatus, of which the following is a specification.

My invention relates to an improvement in photographic apparatus, and has special relation to a new plate-holding box which differs in material respects from others heretofore known to me, the construction and arrangement of which is such that an indefinite 15 number of plates or sensitive surfaces may be carried in the same holder, they being automatically and successively presented at the rear of the camera-box in proper position for exposure, of which exposures also a record is 20 kept, whereby the number of the still sensitive or unused plates may be ascertained at a glance.

My invention also relates to improvements in the means whereby the shutter may be operated and the proper focus obtained.

In the drawings the same reference-letters indicate the same parts in all the figures.

Figure 1 illustrates an edge view of the holder partly in section. Fig. 2 illustrates a 30 side view of the holder partly in section, the shutter being closed. Fig. 3 illustrates a horizontal section of the holder, taken on the line $x-x$ of Fig. 1. Fig. 4 illustrates an elevation of one side of the holder, the shutter being 35 opened. Fig. 5 illustrates a vertical sectional view on the line $y-y$ of Fig. 4. Fig. 6 illustrates a vertical section on the line $x-x$ of Fig. 5.

A is the camera-box, open-ended rearwardly, 40 as now well understood.

B is the plate-holding box, in which the carriers which primarily receive the plates or sensitive surfaces are placed. I will hereinafter call this box B the "plate-holder." The 45 side and edges of the plate-holder are made double-walled, there being a space between them, as at C , Figs. 3, 5, and 6.

D is a partition, which runs horizontally across the plate-holder in its medial line, 50 thus dividing the holder into two substan-

tially equal compartments, E and F . The partition D does not extend entirely across the interior of the plate-holder, there being openings G on each side thereof, through which a plate-carrier may easily drop, as hereinafter set forth.

I and J are two exposure-apertures at opposite ends and on opposite sides of the plate-holder. K and L are two shutters, which respectively close the exposure-apertures I and J . They are 60 operated by means of a pivoted slotted arm, K' , which has a segment-gear, K^2 , on its rear end meshing into another pivoted segment-gear, L' , which has a lever, M , projecting from the side of the plate-holder through a slot, N , 65 made therein.

O is a stud, preferably provided with an anti-friction roller or sleeve, which plays in the slot of the arm K' .

P is a spring-pawl, which is fixed to the arm 70 K' and engages with the teeth of a ratchet, Q , which is fast to an index-plate, R , which has numerals on its face. The numerals register with a hole, S , made in the side of the box.

T is a stop-pawl, which holds the ratchet Q 75 from backward turning.

All the shutter-operating devices just described are inclosed within the double-walled 80 of the plate-holder, and are thus well sheltered and fully protected, excepting the projecting lever M , which is left exposed to allow the operator to manipulate the shutter. It will be seen that these appliances are provided in duplicate—one set for each shutter—and consequently the numbers on the respective index-plates are on one all odd and on the other all even numbers, for the reason hereinafter explained.

The carriers a , a , &c., which support and 90 carry the sensitive surfaces, whether films or glass or other plates coated with the sensitized material, may be made in any preferred manner. They are open-faced at each side, and by the sensitized surface may be exposed, 95 and there is a light-excluding diaphragm between the backs of the sensitized surfaces, as usual in such devices. I prefer to make them of metal and with perfectly smooth and preferably rounded edges and corners, so that their 100

movement within the plate-holder may be accomplished with ease and so that their bulk may be as little as possible. There may be as many of these carriers used as desired, provided their total number is an uneven one—as, for instance, in the illustration there are nine. This is necessary because there must be one more carrier in the compartment when the exposure is first made than in the other one, as will hereinafter appear. The capacity of the plate-holder B is such as to accommodate the desired number, and each of these carriers is numbered on one side with an odd number, commencing with No. 1, and on the other side with an even number, the carrier which is numbered 1 on one side having on its reversed side the even number which is next beyond the total number of carriers. Thus in the present instance the carrier shown in position for exposure in Fig. 5 is numbered 1 on the side which is presented to the camera-lens and 10 on its opposite side. The next one is numbered 3 on the side facing the camera and 12 on the reversed side, and so on. In this manner the numbers 1, 3, 5, 7, 9, 11, 13, 15, and 17 are on one side of the several carriers and 2, 4, 6, 8, 10, 12, 14, 16, and 18 on the reverse sides thereof, respectively; and in placing them in the plate-holder they are so arranged that the odd numbers in sequence face the exposure-aperture of the compartment wherever they are placed, and all the even numbers in sequence face the exposure-aperture in the other compartment, and the odd and also the even numbers should be placed in the compartment to which they severally belong, which will be determined by the index-plates already described, one of them having the odd and the other the even numbers thereon, and the first exposure should be made commencing with the sensitive surface numbered 1.

The operation of the apparatus as thus far described is as follows: The double carriers being each supplied, as stated, with two plates or tablets or films, as the case may be, the outwardly-presented surfaces whereof are sensitive to the action of light, as now well understood, are placed in the several compartments of the plate-holder in the manner described—that is to say, with one more carrier in the compartment containing those having the odd numbers than in the others. The plate-holder is then placed in position against the rear of the camera-box and there fastened, all as now well understood, and as shown in Fig. 5; the lower half of the plate-holder only being then employed in coactive relation with the camera-box. The first exposure is then made by the operation of the shutter-lifting mechanism. (Best seen in Figs. 2 and 4.) During this act the figure 1 on the index-plate is made to appear opposite the opening in the side of the plate-holder, thus indicating that one exposure has been made. The shutter is then lowered by a reverse movement of the shutter-operating

mechanism, during which the index-plate will not be moved, owing to the holding action of the stop-pawl. To make the next exposure, the plate-holder is released from the rear end of the camera, and it is bodily turned over in the hands of the operator, the top being turned toward him, and it is again applied to the rear of the camera-box, as before. The effect of doing this is, first, the carrier bearing the even number which is next in sequence to No. 1—i. e., No. 2—is exposed through the exposure-aperture now presented to the lens, and also the carrier numbered 1 has slid by the action of gravity through the opening in the partition of the plate-holder into the opposite compartment, thus making one more carrier in that compartment, which originally had one less, than in the other. Of course during the turning over of the plate-holder the carriers in the compartment having the less number in it drop by gravity to the lower side of the said compartment, thus making room for the passage of the carrier from the other compartment into it. An exposure is then made of the second plate by an operation of the shutter belonging to the compartment in which it is situated, the same as before, during which the number 2 on its index-plate is brought opposite the opening in that side of the plate-holder, thus showing that two exposures have been made. In this manner, one after the other, all the exposures are made, the carriers, one after the other at successive overturnings of the plate-holder, passing from one compartment into the other, and the indexes will progressively show the number of exposures made, and consequently the number of unexposed or still sensitive surfaces remaining in the plate-holder.

It will of course be seen that the numbering of the carriers is not essential, excepting to show which particular surfaces have been exposed. The indexes will show the number of exposures irrespective of the particular ones exposed; but this latter knowledge is sometimes very essential.

I have not as yet described a part of my apparatus, in order to avoid confusion. It is as follows:

In order that the carriers may move easily under the action of gravity, and that all jamming and sticking may be avoided, it is desirable that the carriers should have very free movement in the plate-holder. Thus there is necessarily considerable "lost motion," so called, possible, which might injuriously affect the correct focal position of the sensitive surface. In order that each exposure may be accurately made and the focus correct, I provide the following mechanism: *k* is a milled thumbscrew, the shank of which carries a little pinion, *l*, located between the double thickness of the edge of the plate-holder. The little pinion meshes into segment-gears *m* on the ends of the two levers *n n'*, pivoted at *o o'*, which are also located between the said double walls, but which are bent at right angles at their

ends o^2 , passing through slots p , cut through the inner wall of the plate-holder into the interior thereof, and they are constructed and arranged to engage with the rear side of the 5 carrier which is farthest from the exposure-aperture of that compartment, and a recess, q , is provided in the side of the plate-holder, into which this right-angle end n of the levers can pass, thus preventing them from interfering 10 with the movements of the carriers.

The operation of this part of my apparatus is as follows: Prior to each exposure the thumb-screw is twisted in the proper direction, which, through the instrumentality of 15 the pinion and the segment-gears, causes the right-angle ends of the levers to move forwardly, pressing the entire number of carriers in the compartment in which the exposure is to take place toward the exposure-aperture. 20 This compels the sensitive surface upon which the picture is about to be taken to assume a correct focal position, which is determined by the sides of the exposure-aperture against which the carrier is thus pressed.

25 It is obvious that my plate-holder may be made of such dimensions that the exposures can be made horizontally, as well as vertically, of the sensitive surface.

I do not limit myself to the details of construction shown and described, because it will be obvious to those who are skilled in such matters that many changes may be made in them and still my invention be employed.

I claim—

35 1. A plate-holding box provided with exposure-apertures at opposite ends and on opposite sides, a light-excluding shutter for each aperture, and a partition across the box having openings therein for the passage of the 40 carriers, substantially as set forth.

2. A plate-holding box having exposure-apertures at opposite ends and on opposite sides, a light-excluding shutter for each aperture, a partition across the box having openings therein for the passage of the carriers, and 45 an index operated at the same time with the shutter, substantially as set forth.

3. A plate-holding box having exposure-apertures at opposite ends and on opposite 50 sides, a light-excluding shutter for each aperture, a partition across the box having openings therein for the passage of the carriers, and means, substantially as described, to secure the proper focal position of the surface 55 about to be exposed, substantially as set forth.

4. A plate-holding box having exposure-apertures at opposite ends and on opposite

sides, a light-excluding shutter for each aperture, a partition across the box having openings therein for the passage of the carriers, an index operated at the same time with the shutters, and means, substantially as described, to secure the proper focal position of the sensitive surface about to be exposed, substantially as set forth. 60 65

5. A plate-holding box having exposure-apertures at opposite ends and on opposite sides thereof, in combination with dual series of sensitive surfaces, one series presented to one of said exposure-apertures and the other to the other, substantially as set forth. 70

6. The combination of a plate-holding box having exposure-apertures on opposite sides 75 and opposite ends with a dual series of sensitive surfaces, one series presented to one of said apertures and the other to the other one of said series, exceeding by one the number of the other series, substantially as set forth. 80

7. A plate-holding box having double sides and edges and provided with exposure-apertures at opposite ends and on opposite sides, shutters for the said apertures, and shutter-operating mechanism, substantially as described, and focusing mechanism, substantially as described, both plates between the double walls of the box, substantially as set forth. 90

8. A plate-holding box having double walled sides and provided with exposure-apertures at opposite ends and on opposite sides, shutters for the said apertures, and shutter-operating mechanism, substantially as described, 95 placed between the double walls, substantially as set forth.

9. A plate-holding box having double walled sides and exposure-apertures at opposite ends and on opposite sides, shutters for the said 100 apertures, and shutter-operating and exposure-indicating mechanism, substantially as set forth.

10. A plate-holding box having double walls and edges, exposure-apertures at opposite 105 ends and opposite sides, shutters to the said apertures, and focusing mechanism, substantially as described, placed between the double walls of the box, substantially as set forth.

Signed at New York, in the county of New 110 York and State of New York, this 30th day of November, A. D. 1888.
